UNITED STATES PATENT OFFICE.

JOSEPH LIPPERT, OF BROOKLYN, NEW YORK.

SCRATCH-GAGE.

1,316,584.

Specification of Letters Patent. Patented Sept. 23, 1919.

Application filed November 20, 1918. Serial No. 263,260.

To all whom it may concern:

Be it known that I, JOSEPH LIPPERT, a citizen of the United States, residing at Brooklyn, county of Kings, and State of New York, have invented certain new and useful Improvements in Scratch-Gages, of which the following is a specification:

This invention relates to improvements in scratch gages and has as its special object the provision of a device in which a movable bar is spring clamped when in an adjusted position and provided with a marking or scratching means of novel form.

A further object is to provide a device of the class described of an attractive design, which may be operated without screws or clamping means ordinarily employed.

These and other like objects are attained by the novel construction and combination of parts hereinafter described and shown in the accompanying drawings, forming a material part of this disclosure and in which—

Figure 1 is a perspective view showing a scratch gage made in accordance with the invention.

Fig. 2 is a vertical sectional view taken through the center of the same.

Fig. 3 is a transverse sectional view taken on line 3—3 of Fig. 2.

Fig. 4 is a partial side elevational and sectional view showing a modified form of the scratch carrying bar.

Fig. 5 is a perspective view showing the clamp plunger used in connection therewith, and

Fig. 6 is a transverse sectional view, similar to Fig. 3, but showing a modification of construction.

In carrying out the invention use is made of a plate 10, which may be rectangular, circular or of any other desired contour, and formed integrally therewith is a transverse cylindrical extension 11, its axis being parallel with the face of the plate 10, while extending rearwardly, at a right angle from the extension 11, is a smaller cylindrical extension 12, through which is a central bored opening 14 the same extending through the plate 10, and adapted to receive a round bar 15, which may be graduated, as indicated at 16, its entire length and screwthreaded at one end to receive a screw 18, the head 19 of which serves to clamp a disk 20, the same being formed with a beveled marking periphery.

The cylindrical extension 11 contains a

circular recess 22 to which is fitted a plunger 23, so as to slide freely therein, the plunger having an elongated slot 24, through which the rod 15 freely passes, a part of the plunger 23 extending beyond the end of the cylindrical extension 11, so as to be pressed inwardly by the thumb when it is desired to adjust the bar or by mechanical means if preferred.

Set in the inner end of the plunger 23 is a screw 25, and encircling the head of the screw is a coiled compression spring 26, one of its ends pressing the plunger 23 normally outward while the other end abuts against the inner or bottom portion of the recess 22.

The point of the screw 25 is preferably made concave so as to obtain an efficient grip or bite upon the rod 15 holding it, under pressure of the spring, in an adjusted position, movement being effected by pressing the plunger 23 inward and then sliding the bar 15 as may be desired.

In the form shown in Fig. 4, the outer surface of the bar is corrugated, knurled or otherwise roughened, as at 28, thereby affording a better grip for the point of the screw to prevent it from moving longitudinally when in adjustment.

In the modification shown in Fig. 6, the screw 25 is formed with a sharp conical point 25', adapted to engage in a V shaped groove 15' formed longitudinally in the rod 15, acting as a key and preventing the rod from turning as well as holding it in adjustment.

From the foregoing it will be seen that an efficient, neat and easily operated device for marking has been disclosed, which always presents a substantially sharp marking edge on the beveled disk 20, which can be removed and sharpened and replaced in an obvious manner, while adjustment of the bar 15, relative to the body, is easily accomplished by pressing the plunger 23 and moving the bar so as to register any desired distance between the base 10, and periphery the disk 20 in a manner which will be clearly apparent.

Having thus described my invention what I claim as new and desire to secure by Letters Patent, is—

1. In a scratch gage, the combination with a body having a cylindrical extension, of a bar slidable through said extension and said body, a marking device carried at one end

of said bar, a plunger having a slot through which said bar freely passes, and a spring fixed in said body adapted to press said plunger normally outward.

- 5 2. In a scratch gage, the combination with a body having a face plate and an extension opposite to said face plate, said body containing a longitudinal passage at a right angle to said face plate, and a transverse opening parallel to said face plate, of a bar adapted to slide through the mentioned passage, a circular disk having a sharpened periphery removably engaged at one end of

said bar, a plunger slideable in the transverse opening formed in said body, said plunger having an elongated recess through which said bar may pass, a screw fixed in the inner end of said plunger, said screw having a point adapted to contact with said bar, and a spring in said recess encircling the head 15 of said screw, adapted to press said plunger normally outward causing said screw to engage with said bar. 20

In testimony whereof I have affixed my signature.

JOSEPH LIPPERT.
